THRESHOLD

Fred W. Kammerer, New York, N. Y.

Application May 26, 1937, Serial No. 144,931

14 Claims.

(Cl. 20—64)

This invention relates to a new and improved threshold construction, adapted for use as a door sill, or as a window sill for windows of a particular type. The invention also contemplates certain improved combinations of threshold constructions with windows and doors of unusual types.

It is a primary object of the invention to provide a threshold comprising interengaging extruded metallic sections which may be assembled for relative pivoting movement. The sections may be joined together before their installation on the sill of a door or window, but, when once assembled and installed, they cannot become separated accidentally.

It is a further object of the invention to provide a threshold or sill construction for vertically sliding windows of the type which extend from a convenient height in the wall, substantially down to the floor level, and which may be stored in a pocket formed in the wall below the floor level. In this connection, the invention contemplates the provision of a pivotally mounted section adapted to be swung from a horizontal position, where it serves as a closure for the mouth of the pocket, to a substantially vertical position to give access to the pocket so that the sashes may be placed in or removed from the pocket.

It is a further object of the invention to provide a novel form of threshold construction, or door saddle, which, in some respects, is an improvement on the door saddles described and claimed in my copending application Serial No. 70,530, March 23, 1936.

In the accompanying drawings, three embodiments of the invention are disclosed for purposes of illustration, but it must be understood that the invention is not limited to the details of construction shown therein and described below.

In the drawings:

Figure 1 is a vertical sectional view of a window construction showing the use of the threshold of the present invention, central sections of the window panels being broken away for economy of space.

Figure 2 is a vertical sectional view of a slight modification.

Figure 3 is an enlarged sectional view of a preferred form of joint between the sections of the threshold.

Figure 4 is a transverse vertical section of a modified form of sill or threshold member, and

Figure 5 is a similar view of the device of

Figure 4, showing the parts in a different position.

Referring to the accompanying drawings, the threshold comprises a pair of sections or members 10 and 11, preferably formed of extruded metal, such as brass, bronze, or the like. The inner section 10 is formed with a tread portion 12 terminating inwardly in a down-turned marginal flange 13 provided on its undersurface with serrations or the like 14, adapted to grip the floor or other supporting surface adjacent the window opening. The section 10 also comprises a channel section 15 having similar serrations 16 on its undersurface. The outer wall of the upwardly opening groove or channel 17 is in the form of an upstanding flange 18 terminating in a cross-sectionally rounded bead or head 19. The section 10 may be secured in place adjacent the window opening by wood screws 20, or any suitable means.

If desired, the channel or groove 17 may be provided with a plurality of holes 21, to permit the escape of any water which may, perchance, collect therein.

The section 11 comprises an upper, substantially horizontal jamb section 25 and a flat, downwardly inclined portion 26. The section 26 may be provided at its edge remote from the section 10, with a down-turned flange 27 provided with serrations 28 thereon. On the undersurface of the section 11, below the jamb portion 25, there is formed a longitudinally extending, cross-sectionally rounded groove 29, complementary in shape to the bead 19, and embracing slightly more than one-half of the circumference of the bead. Thus, the two sections may be assembled only by relative endwise movement. When they once have been assembled, they cannot be separated by relative transverse movement, because the groove 29 is of reentrant form and embraces the bead.

In certain types of constructions, it is advantageous to provide the flat portion 26 of the section 11 with an upstanding rib or the like 30, to cooperate with a weather strip or groove 45 associated with a window or door to provide a weathertight joint, as described below.

As stated above, the threshold of the present invention is particularly adapted for use with sliding windows of the type that drop down into a pocket formed in the wall of the building, below the window opening. Constructions of this class are often used for windows leading from a house to an outside porch. Such an installation is shown in Figure 1. The upper window 55

- panel 35 slides in a vertical slideway 36, which continue down below the bottom edge 37 of the window opening and merge with a slideway 38 in the wall pocket, represented generally at 39.
- 5 Likewise, the lower sash or panel 40 is mounted in a slideway 41, which continue downwardly as at 42 in the pocket. The window opening is provided with an exterior screen 45, which may also slide down into the pocket 39.
- 10 When it is desired to dispense with the sashes or panels and completely open the window, the lower sash 40 may be raised somewhat and the section 11 of the threshold swung upwardly, about the bead 19 as a pivoting axis. As shown in Figure 3, the parts are so proportioned that the pivoted section may be raised to a substantially vertical position. Thereupon, both the upper and the lower sashes may be dropped downwardly for storage in the pocket 39. When the section 11 of
- 15 the threshold is raised, the mouth 45 of the pocket is uncovered, for this purpose, and, after the panels have been stored, the pivoted section of the threshold is simply swung downwardly to the substantially horizontal position, whereupon the
- 20 pocket is closed.
- 25 The rib 39 projects into a groove 30' formed along the bottom edge of the lower panel 40, to provide a weathertight joint. In the alternative, any convenient form of the weather strip may be used to cooperate with this projecting rib.
- 30 In Figure 2, the invention is shown as a saddle for swinging doors. In this case, a door 50 is hinged for swinging movement toward and from the closed position shown in the drawings, above
- 35 the jamb section 26 of the saddle. The flat portion 26 is inclined downwardly and outwardly toward a screen door 51. The same type of joint may be used to connect the inner section 12 and the outer section 11 as in the construction previously described.
- 40 As an added feature of great utility, I provide an edge strip 52, adapted to embrace the raw edge 53 of the section 26. Such an edge strip is advantageous because, when thresholds of this type are installed, the workman often cuts them down, to diminish their width,
- 45 by sawing off a marginal portion of the section 26 with a hacksaw. Unless great care is used, this operation results in a rough, raw edge, which is not only unsightly, but often results in an uneven fit with the floor. The edge strip 52 is preferably
- 50 in the form of a flattened C-section, comprising an upper flange 53 and a lower flange 55, joined by a short web 56. Serrations or the like 57 are provided on the lower surface of this member, to resist slippage on the floor. Since the member
- 55 54 fits the section 26 quite snugly, it can only be applied and removed by relative movement in a plane parallel to the plane of the flat portion 26. After the sections have been screwed down by
- 60 wood screws 58 or the like, the edge strip will be held firmly in place because movement in a plane parallel to the flat portion 26 will be impossible by reason of the abutting relation of the floor thereto.
- 65 As pointed out in my copending application referred to above, a saddle comprising two sections pivoted together is of material advantage to compensate for differences in the floor levels adjacent a door sill. Moreover, the pivoting action enables the inclined section 26 to accommodate itself to different angles of inclination, which invariably results when the section is cut down or otherwise changed in width. Obviously, if the movable section 11 is wide, a relatively flat
- 70 angle of inclination will result. However, if a
- 75

narrow threshold is desired and the portion 26 of the section 11 is cut down, a steeper angle of inclination will result. This action is permitted by a pivoting movement between the sections 11, 12.

The modified form of sill or threshold member 5 shown in Figures 4 and 5 is preferred, for many installations. Since this construction is generally similar to that shown in Figures 1 and 2, all of its details will not be described, like parts on the modified form being referred to by the same characters as in the first form. The principal difference resides in the form of the pivotal connection between the sections 10' and 11'. The upstanding flange, to which the movable section is connected, instead of being made integral with the stationary section, is in the form of a separate metallic strip, pivotally connected to the two sections, thereby increasing the range of pivoting movement between the sections.

As shown in Figure 4, the lower horizontal section 15 of the section 10' is provided with a pair of upwardly projecting flanges 60, 61, shaped to provide therebetween, a cross-sectionally rounded, re-entrant groove 62. The groove 29' formed in the other threshold section is substantially the same as the groove 29 in Figures 1 and 3, with the exception that its inner walls extend around and form a more restricted mouth.

The sections 10', 11' are connected together by a metallic strip 63 of special cross-sectional shape having its edge portions 64, 65 enlarged and cross-sectionally rounded to substantially circular form, as shown in the drawings. These enlarged, beaded edges are disposed in the grooves 29', 62 respectively, the parts being assembled by relative endwise movement. Because of the re-entrant shape of the grooves, and the enlarged form of the beaded edges of the connecting link member 63, the parts cannot be separated by relative transverse movement, but can be assembled and taken apart only by relative endwise movement. The member 63 is preferably made of extruded metal section, but, since its cross-sectional shape is relatively simple, it may be rolled out of circular or flat stock.

The advantage of this form of the invention is illustrated in Figure 4. The pivoting movement of the member 63 with respect to the member 10' permits the movable section 11' to be swung back to or beyond the vertical line. Thus, when the threshold section 11' is lifted to the position shown in Figure 5, the windows may be moved into and taken out of the pocket 38 with facility, and it is not necessary for the person manipulating the windows to manually hold the section 11' in the upright position.

The pivoting action of the member 63 increases the degree of swinging movement of the member 11' relative to the section 10', and makes it possible to construct the grooves so that they embrace a larger portion of the interengaging, rounded ribs. Therefore, the parts need not fit as closely as in the first form of the invention. If the groove formed in the member 11 in the form shown in Figure 3 is made more re-entrant, the edges of the groove will abut the rib 18 before the section can be swung to the vertical position and this result is undesirable.

As stated above, the present invention is not limited to the details of construction shown and described herein, but includes all modifications coming within the scope of the appended claims or their equivalents.

I claim:

1. A threshold construction for windows and

75

the like comprising a pair of pivotally connected sections, one of said sections having a longitudinally extending, upwardly facing channel bounded along one edge by a substantially vertically 5 projecting, upstanding flange, said flange being provided at its upper end with an enlarged, cross-sectionally rounded head, the other section of said pair comprising an upper, substantially horizontal jamb portion and a downwardly inclined 10 approach portion projecting laterally therefrom and connected integrally therewith, and adapted to underlie the associated door or window, the undersurface of the jamb portion being shaped to form an elongated, downwardly facing, cross- 15 sectionally rounded groove, said groove being complementary in shape with and adapted to embrace the head on said flange, said groove and said head being of such relative size and shape and being so constructed and arranged as to 20 permit the second section to be swung upwardly to lie in a substantially vertical plane disposed laterally from the plane of the associated window.

2. A threshold construction comprising a pair 5 of interengaging metallic sections, one of said sections having a longitudinally extending, upwardly facing channel and an upstanding flange pivoted to said member along one edge of the channel, said flange being formed at its upper 10 end with a cross-sectionally rounded head, the other section of said pair being provided with a cross-sectionally rounded socket adapted for pivotal connection with said head, said other section being adapted to extend across the lower 15 edge of an associated door or window opening to underlie the closure therein.

3. A threshold construction comprising a plurality of interengaging metallic sections, one of said sections having a longitudinally extending, 0 upwardly facing channel adjacent one edge, a flange pivotally mounted in said channel, said flange having at its upper end an enlarged, cross-sectionally rounded head, and another section having a cross-sectionally rounded socket adapted 5 for pivotal connection with said head, said last-mentioned section being adapted to extend across the lower edge of an associated door or window opening to underlie the closure therein.

4. A threshold construction comprising a pair 0 of interengaging metallic sections linked together, one of said sections having a longitudinally extending, upwardly facing channel, and an upwardly projecting flange associated with said member along one edge of said channel, said 5 flange being formed at its upper end with a cross-sectionally rounded head, the other section of said pair being provided with a cross-sectionally rounded socket adapted for pivotal connection with said head, said second section being projected laterally away from the first section and from said connection and being adapted to extend across the lower edge of an associated door or window opening to underlie the closure therein and being provided with an 10 upwardly projecting flange adapted to project into a groove associated with the lower edge of the closure to provide a weather-tight joint.

5. A threshold construction comprising a pair 0 of metallic sections connected together for relative pivotal movement along their adjacent edges, and a metallic finishing edge strip for the opposite edge of one of said sections, said strip comprising a flat C-section having its parallel flanges engaging the upper and lower faces of that section along said edge.

6. A threshold construction comprising a pair of metallic sections connected together for relative pivotal movement along their adjacent edges, and a metallic finishing edge strip for the opposite edge of one of said sections, said strip comprising a flat C-section embracing and concealing the edge. 5

7. A threshold construction comprising a pair of metallic sections connected together for relative pivotal movement along their adjacent edges, one of said sections having a flat portion inclined downwardly from the zone of junction with the other section and terminating in a raw edge, and a finishing and supporting strip for said edge, said strip comprising parallel flanges 15 closely embracing the opposite faces of said inclined portion, whereby said strip can be applied to and removed from the section only by relative movement in a plane parallel to the faces of said section, and means for securing said section in inclined relation to a supporting surface with the strip contacting the surface, said securing means serving to prevent removal of said strip. 20

8. The combination with a metallic threshold 25 having a flat portion inclined downwardly toward a supporting surface, of a finishing and supporting strip for the lower edge of said portion, said strip comprising parallel flanges closely embracing opposite faces of said inclined portion, whereby said strip can be applied thereto and removed therefrom only by relative movement in a plane parallel to the plane of the faces of said portion, and means for drawing said portion and said strip downwardly toward the supporting surface, whereby said strip is secured in place. 30

9. In a window frame construction comprising a window opening having vertical slideways for 40 sliding panels and a pocket in the wall below said opening having continuations of said slideways to facilitate storage of the panels in the pocket, a sill for said opening comprising elongated metallic sections of substantially equal length pivotally connected together, one of said 45 sections being secured to the frame along one edge of the mouth of said pocket and extending entirely across the window opening and the other section being secured substantially throughout its length to the first-mentioned section and being mounted for swinging movement from a substantially horizontal position closing said mouth to a substantially vertical position opening said mouth to give access to said pocket. 50

10. In a window frame construction comprising a window opening having vertical slideways for 55 sliding panels and a pocket in the wall below said opening having continuations of said slideways to facilitate storage of the panels in the pocket, a sill for said opening comprising metallic sections pivotally connected together, one of said sections being secured along one edge of the mouth of said pocket and comprising an upstanding flange terminating in a cross-sectionally rounded head, the other of said sections extending laterally away from the first section and having, along its adjacent edge, a complementary, cross-sectionally rounded socket on its undersurface embracing said head, to permit pivotal movement of the second section from a substantially horizontal position closing the mouth of said pocket to a substantially vertical position giving access thereto. 60

11. In a window frame construction comprising a window opening having vertical slideways 70

- for sliding panels and a pocket in the wall below said opening having continuations of said slide-ways to facilitate storage of the panels in the pocket, a sill for said opening comprising inter-
5 engaging metallic sections, one of said sections being secured along the bottom of the opening adjacent the mouth of said pocket and being pro-
vided with an integral cross-sectionally rounded bead extending substantially entirely across the
10 opening, the second section having a cross-sec-
tionally rounded groove of corresponding length embracing said bead throughout more than half
of its circumference, whereby said sections may
15 be formed together and separated from interen-
gaging relationship only by relative endwise
movement, the second section being swingable
from a position closing the mouth to said pocket
to a position giving access thereto to permit stor-
age of the panels therein.
20 12. A sill construction comprising extruded
metal sections linked together for relative pivoting
movement, said sections being shaped along
their adjacent edges to provide elongated grooves,
and a connecting element for said sections com-
25 prising an elongated metallic strip having round-
ed portions along its opposite edges adapted to
be received in said grooves respectively.

13. A sill construction comprising extruded
metal sections linked together for relative pivot-
ing movement, said sections being shaped along
their adjacent edges to provide elongated, re-
entrant, cross-sectionally rounded grooves, and a
connecting element for said sections comprising
an elongated metallic strip having enlarged,
cross-sectionally rounded edge portions and a re-
duced connecting body, said edge portions being
received in said re-entrant grooves to prevent
separation of the parts by relative transverse
movement.

14. A sill construction comprising extruded
metal sections adapted to be secured together by
relative endwise movement and to resist separa-
tion by relative transverse movement, said sec-
tions being shaped along their adjacent edges to
provide elongated re-entrant, cross-sectionally
rounded grooves, and means for connecting said
sections together, said means comprising an
elongated metallic strip having enlarged, cross-
sectionally rounded, beaded edge portions and a
reduced intermediate body portion, said beaded
portions being receivable in said grooves of said
sections by relative endwise movement only.

FRED W. KAMMERER.
